UNITED STATES PATENT OFFICE.

FRANK C. DOBLE, OF WINCHESTER, MASSACHUSETTS.

HIGH-TENSION TELEPHONE SYSTEM.

1,350,922.

Specification of Letters Patent. Patented Aug. 24, 1920.

Application filed July 30, 1919. Serial No. 314,365.

To all whom it may concern:

Be it known that I, FRANK C. DOBLE, a citizen of the United States, residing at Winchester, in the county of Middlesex and 5 State of Massachusetts, have invented new and useful Improvements in High-Tension Telephone Systems, of which the following is a specification.

The present invention has reference to 10 telephone systems arranged in parallel with high tension electric transmission lines. Telephone systems so provided are generally the private lines of companies operating high tension power lines, and they are all 15 most universally strung upon the towers which carry the line wires of the power system, on account of the obvious advantages of economy in equipment, maintenance and protection. The protection afforded by 20 this manner of running the telephone line includes both protection from lightning, for the telephone line is screened by the transmission line and the protections of that line against the effects of lightning, and from 25 theft of wire and malicious damage. However, telephone lines so carried, and also any lines running parallel and near to transmission lines, are charged with high potential, even under conditions of normal 30 operation of the power transmission lines, while they are additionally subject to great disturbances under abnormal conditions, such as switching over the transmission line, arcing grounds, lightning disturbances, etc., 35 which cause by their inductive effect surges of extremely high voltage in the telephone lines.

Heretofore, the telephone systems arranged and used as above indicated, have 40 been low tension systems, which are intended to be so arranged that no other part of the system than the circuit or line wires can maintain high tension conditions. Any low tension system is very difficult to maintain, even under the best normal operating 45 conditions of the adjacent high tension transmission line, while any of the abnormal conditions such as those above mentioned not only render the telephone system 50 dangerous to the operators, but may also destroy the apparatus.

It is the purpose of the present invention, which I desire to protect herein, to furnish a high tension telephone system, in which 55 all parts, including not only the circuit or line but also the instruments, are capable of

maintaining a high voltage with respect to the earth potential, and of being operated safely and with satisfactory results in the intelligible transmission of speech, under 60 practically all conditions, and, in any event, under many of the conditions which render a low tension system inoperative, or even destroy it.

The principles of the invention, and the 65 manner in which at present I put them into effect, are disclosed in the following specification, and pointed out in the appended claims, in connection with the drawing referred to in said specification. 70

In this drawing:

Figure 1 is a diagram of a high tension telephone system embodying my invention, including, for illustration, a central station, 75 and two local stations.

Figs. 2 and 3 are respectively a front and a side elevation of a telephone instrument containing some of the means which I have provided as a part of the invention, for protecting the operator from harm from excessive potentials in the system. 80

Fig. 4 is an elevation, as seen from the left of Fig. 2, of the protection which guards the receiver hook. The same protection is shown in Fig. 2, as a section taken on line 85 A—A of Fig. 4.

Like reference characters indicate like parts in all of the figures.

Definitions.—Wherever in this specification, the following words are used as referring to the high tension telephone system in which the present invention is embodied, 90 they are to be understood as having the following meanings:

“Circuit” is understood to mean an arrangement of wires connecting two or more points between which communication is desired. 95

“Instrument” is understood to mean apparatus arranged for transmitting and receiving electrical impulses over the “circuits” in a manner which reproduces sounds or signals, and most particularly the sounds of articulate speech. 100

“Station” is understood to mean a booth or platform, to which the instruments are, or may be, attached, and which is occupied by the “operator” when using the “system.” 105

“Protection” is understood to mean a 110 combination of apparatus which safeguards the “operator” and parts of the “system”

from excessive potentials and dangerous electrical disturbances.

"System" is understood to mean a combination of "circuits," "instruments," "stations" and "protection" which as a whole permits "operators" to communicate safely.

"Operator" is understood to mean a person who uses the "system" as a means of communication.

- 10 Referring now to Fig. 1, "station" A represents a central station in the high tension telephone system, and this may be the main office, or the despatcher's office of the power transmission line, or it may be any other station where two or more telephone lines enter, and from which communication may be had with local stations, or by which local stations may be connected for communication one with another. "Station" B and
 15 "station" C represent two of the local stations in the system to illustrate the principle of the invention. In each local station, *a* represents a booth, which may be an inclosed chamber, or simply a support of any suitable character to mount the telephone instrument *b*, having a platform or floor *c*, on which the operator may stand.
 20 *d*, *e*, and *d'*, *e'* represent the line wires of the system between the local stations and the central station respectively. It is to be understood that these line wires may be strung on the towers of a high tension power line, or on separate poles, in any approved way, and secured by any approved means.
 25 At *f* is shown diagrammatically, for illustration, an insulator arranged to support one of the wires. It may be understood, without further illustration or statement, that this insulator represents one of the telephone wire supporting insulators on one of the towers or poles, and that all of the lines may be supported by like or equivalent insulators.

30 The branch connections from the line wires of the circuits to the respective instruments are substantially alike in all cases, and all such connections necessary for the stations represented in the diagram are shown in Fig. 1 in parallel, with the corresponding elements of the protection in the several branches beside one another, and designated by proper legends. The branch connections leading to all the instruments are designated by the same reference letters, 35 *g* and *h* respectively. A horn gap is provided to ground from each side of the branch connection, to drain off surges of the highest potential in the circuit. Disconnect switches are located in both sides of the branch, and are intended to be normally closed. On the station side of the disconnect switches are two sets of choke coils, one coil of each set being in each side of the branch, and between the two sets of choke coils are
 40 a cylinder and a vacuum arrester across the
 45 branch, and horn gaps from each side of the branch to earth. The purpose of these choke coils is well known and understood; that of the horn gaps is to discharge excessively high potential, and that of the cylinder gap 70 and vacuum arrester to equalize the potential in both sides of the branch, whereby to obtain the balance necessary for avoidance of objectionable sounds in the instrument.

75 In this description, the term "branch" is intended to mean the wires which run to the instrument from the line, whether such wires are in fact the ends of the line wires at a terminal station or shunt wires cut into the 80 line at intermediate points. In other words, the wires running to any instrument in the system are considered as a branch within this definition.

85 The booth is highly insulated from the ground by means of insulated supports *j*, *j*. It is also preferably raised to such a high elevation above the ground that it cannot be entered except by the person entering it first stepping upon a step *k*, at a lower elevation, but also insulated from the ground by insulated supports *l*, *l*; this step, of course, being likewise of such wide dimensions in each direction that an operator in the booth can not even reach over and make 90 contact with a person standing on the ground. This insulation safeguards the operator from ground, not only by making it impossible to speak into the instrument while standing on the ground, but also by 95 preventing a casual and accidental contact, which might occur through handing something to a person standing on the ground.

100 Further protection from ground, provided on the instrument itself, is shown 105 particularly in Figs. 2, 3 and 4, and consists of a non-conducting box *m*, inclosing the local circuit and connections of the instrument, a case *n* on the front of the box, inclosing a transmitter and leaving only the 110 non-conducting mouthpiece exposed; a guard *o*, overhanging and surrounding the hook *p* on which the receiver *q* is supported when not in use, in the usual manner; and insulating protection for the crank of the 115 magneto in the signaling circuit. The last-named protection consists of disks *r* and *s* of insulating material, inclosing the crank on the magneto or motor, and a handle *t*, likewise of insulating material, secured to 120 said disks.

125 The central station is protected by essentially the same means as the local stations, such means including the insulated platform *c'* and insulated step *k'*, and protections for the instrument. In the diagram there is indicated in connection with the central station means by which the instrument of that station may be connected with any of the local station instruments, and by which any 130

of the local stations may be connected with one another. These means comprise two pairs of bus bars, 1^a, 2^a and 1^b, 2^b, having contacts for double-throw switches, which 5 are connected with the central station instrument and with the several circuits respectively. The locations of these double-throw switches are designated at 1, 2, 3 and 10 4. It is intended by this illustration to indicate that any number of circuits may be brought into the central station, with provisions for coupling them, as described.

To complete the disclosure of protection, I have also shown in the diagram means to 15 insulate a power ringing device at the central station from ground. The ringing device comprises a generator 10, connected in the ringing circuit, in which there is a switch, controlled by the operator and indicated at 13, and an electric motor 11, mechanically connected to the generator by a 20 shaft 12. The generator, ringing circuit and switch are protected by the insulation of the operator's station, but the motor is not so 25 protected and may be connected in any power circuit which is not protected, or may not be protected, against discharge of such high potentials as may be imposed on the telephone system. Hence the motor is 30 considered as ground with respect to my system, and the safeguard or protection against discharge to ground at this point is afforded by making the power shaft 12 likewise an insulator of sufficiently high resistance to prevent discharge. Materials suitable 35 for an element of this sort, which is at the same time a power transmission means and an insulator, are wood, hard fiber and various other known materials.

40 Briefly summarizing the features of the invention which I have just described at length, the system consists of:—

First. A very carefully constructed and 45 highly insulated circuit, all parts of the circuit being supported by insulators of such high resistance as to prevent short circuiting by the highest voltages liable to be imposed on the telephone system.

Second. Instruments which are preferably 50 connected directly to the circuit, and have all metallic connections or terminals insulated against possible contact with the operator. This feature of the direct connection between the instrument and the circuit 55 is highly important because it greatly augments the clarity and intensity of sound transmission; and it is made possible by the protection afforded by the high resistance insulation.

60 Third. Very highly insulated stations, constructed and guarded to prevent the operator using them from making direct connection to earth.

Fourth. Protection which prevents high 65 potential between parts of the system, and

offers only a very high resistance path to the ground, which relieves the system of abnormally high potentials. The protection here referred to includes the horn gaps, choke coils, cylinder gap and vacuum arrester previously described. While the horn gaps permit discharge to ground, they are nevertheless of such high resistance that they permit discharge only of excessively high charges, and no attempt is made to 70 bring the potential in the circuit at all near the earth potential. The cylinder gap and vacuum arrester merely equalize potential in the circuit on opposite sides of the instrument, to secure the balance essential to obtaining a quiet line.

I have found by experience that, as a result of the novel characteristics previously described and above summarized, a telephone system is obtained, which is not liable 85 to destruction or even derangement by abnormal conditions encountered in high tension transmission service, over which conversation can be carried on, even when such abnormal conditions exist, in practically all 90 cases except, possibly, at and immediately after a stroke of lightning, and in the use of which the operators are safeguarded. The system is, under normal conditions, at a potential greatly above that of the earth; but 95 the operator is protected by the secure insulation and other protections from practically all shocks, and certainly from shocks of such force as could cause death or injury; while the direct connection of the instrument to the line, and the fact that all parts 100 of the line are at substantially the same potential, make intelligible conversation possible under conditions where the low tension system would be altogether useless.

105 The system thus described is operative under all the conditions in which any low tension telephone system is operative, and also under conditions where, for example, the induced pressure on the system is of an 110 order of magnitude of thousands of volts, conditions in which the low tension system may not be operative at all. When there is no voltage in the power line, there is no appreciable impediment to transmission of 115 speech in the telephone system, on account of the fact that the instruments are directly connected to the line without intermediate transformers or drainage coils. It is thus made possible by my invention to communicate over the telephone line at any and all times, except at the instant of actual lightning stroke or similar disturbance; while the danger to the operators is reduced to the minimum and is much less than with other 120 systems when operating under like conditions of disturbance.

What I claim and desire to secure by Letters Patent is:

1. A high tension telephone system having 130

all its parts insulated from ground and so designed that no part of the system will break down to ground under a sustained electrical stress less than one thousand volts pressure (root mean square sine wave value) at any frequency; and comprising as such parts a circuit, a telephone instrument and an operator's station.

2. A high tension telephone system, comprising a circuit adapted to run in proximity to an electric power transmission line, and having means for substantially equalizing the potential in all parts thereof, a telephone instrument in direct connection with said circuit, and high resistance insulating means adapted to sustain an electrical stress up to one thousand volts (root mean square sine wave value) interposed between ground and the position of the person using the instrument.

3. In a high tension telephone system, a telephone station including an instrument removed from ground; a platform whereon the operator may stand, and insulating means supporting said platform and having resistance effective to prevent discharge of a sustained electrical stress of less than one thousand volts pressure (root mean square sine wave value) at any frequency, from the instrument or operator to ground.

4. A high tension telephone system embodying the combination with line wires of a branch circuit, a telephone instrument in direct connection with the wires of said branch circuit, air gaps between the wires of said branch circuit and the ground to discharge excessively high potential in the circuit, means to equalize the potential in both sides of the branch, and an operator's station, all said parts being insulated from the ground to withstand breaking down under a sustained electrical stress of one thousand volts (root mean square sine wave value).

5. In a high tension telephone system, an operator's station comprising a platform, high resistance insulation supporting said platform, an instrument at such a height

above said platform that an operator in using it is compelled to occupy the platform, and an approach step to the platform also insulated from the ground and being arranged to serve as a guard preventing contact between an operator using the telephone and a person on the ground.

6. In a high tension telephone system, a telephone instrument having the usual receiver hook for supporting the receiver, a transmitter, and suitable circuits, and comprising also insulating material inclosing all metallic parts of the instrument.

7. A high tension telephone system, comprising a circuit adjacent to an electric power transmission line, means for grounding surges of excessively high potential in said system while maintaining the potential of the system relatively high above the earth potential, means for equalizing the potential in the circuit, a telephone instrument directly connected to the circuit, insulating means in connection with said instrument, arranged to guard the metallic parts thereof from contact with an operator using the instrument, and a raised and highly insulated platform for the operator.

8. A high tension telephone system, comprising a circuit adjacent to an electric power transmission line, means for grounding surges of excessively high potential in said system while maintaining the potential of the system relatively high above the earth potential, means for equalizing the potential in the circuit, a telephone instrument directly connected to the circuit, insulating means in connection with said instrument, arranged to guard all metallic parts thereof from contact with an operator using the instrument, a raised and highly insulated platform for the operator, and a guard preventing contact between an operator using the instrument and a person standing on the ground.

In testimony whereof I have affixed my signature.

FRANK C. DOBLE.
